Primary Examiner — Susan E Krakower(74) *Attorney, Agent, or Firm* — Leanne Taveggia Farrell; Westman, Champlin & Koehler, P.A.**CLAIM**

The ornamental design for a display fixture, as shown and described.

DESCRIPTION

FIG. 1 is a top perspective view of a display fixture showing our new design;

FIG. 2 is a partial enlarged view of FIG. 1;

FIG. 3 is a front view thereof;

FIG. 4 is a right side view thereof;

FIG. 5 is a left side view thereof; and,

FIG. 6 is a top view thereof.

The broken lines shown in the drawings are included for purposes of illustrating portions of the display fixture or for purposes of illustrating environment and form no part of the claimed design. The vertical lines representing a structure that is visible beyond the horizontal elements form no part of the claimed design.

1 Claim, 4 Drawing Sheets(56)
